UNITED STATES PATENT OFFICE.

NORMAN S. PAGE, OF NEW YORK, N. Y.

PARTY-LINE TELEPHONE SYSTEM.

No. 873,588.

Specification of Letters Patent.

Patented Dec. 10, 1907.

Application filed January 17, 1907. Serial No. 352,715.

To all whom it may concern:

Be it known that I, NORMAN S. PAGE, a citizen of the United States, and a resident of the city of New York, borough of Manhattan, 5 in the county and State of New York, have invented a new and Improved Party-Line Telephone System, of which the following is a full, clear, and exact description.

My invention relates to party line telephone systems, my more particular object being to provide a line with a relay or equivalent member so arranged that when this relay is energized it performs a double office, to wit: First it allows any telephone on a line to 10 be connected up ready for ringing and talking, provided no other telephone on the same line is already in use; and second, it operates to complete the bell circuit so that the bell may ring to announce the incoming call. 15 Both of the operations just mentioned have heretofore been accomplished by means of separate relays but I combine the two operations in the work by a single relay.

Reference is to be had to the accompanying drawing forming a part of this specification, in which the figure shows a diagrammatic representation of a central station and a party line, all parts being in their normal positions.

20 Two subscribers' stations are shown at A, B. A central station appears at C.

A line lamp 1 is located at the central station for the purpose of producing alarms when the subscribers upon the party line desire to attract the attention of the central operator. Wires 2, 3, connect the line lamp 1 with a battery 4 or equivalent source of electricity, and the latter is connected by wires 6 and 7 with a line relay 5. This relay 25 is provided with an armature 8 and a contact 9 in the manner well understood in this art. Connecting the contact 9 with the wire 6 is a wire 10; a wire 11 extends from the armature 8 to the line lamp 1. A wire 12 connects the line relay 5 with a jack 13 and from the latter a wire 14 leads to the wire 3. The arrangement is such that when the line relay 5 is energized and the contact 9 thereby closed, the line lamp 1 is lighted by current from the 30 battery 4.

A plug 15 is connected by wires 16, 17, with the contact springs 19, 20, of a ringing key 18; a ground wire 21 is connected with a contact member 22 against which the contact spring 19 is adapted to move. Another wire 23 is connected with a contact wire 24

and with a generator 25. The latter is grounded by means of a wire 26. From a contact member 28 a wire 27 leads to a repeating coil winding 29, the latter being connected with a battery 34 and windings 29^a, from which a wire 30 leads to a plug 31 similar in all respects to the plug 15. This plug is connected by a wire 32 with windings 33^a, 33, the latter being connected with the 40 battery 34. The repeating coil windings 33, 33^a, are further connected by a wire 35 with a contact member 36. Ringing is accomplished by inserting the plug 15 into the jack 13 and depressing the ringing-key 18 in 45 the usual manner. Line wires 37, 38 are connected with the jack 13 and extend to each station from the party line. At each station A, B, upon the party line is located a high resistance relay 39 connected by a wire 40 with the line wire 37, also connected by a wire 41, condenser 42 and wire 43 with the line wire 38. Contact members 44, 45, are connected respectively with the wires 41, 61. A traveling contact member 46 is mounted 50 upon a sector 47, and by means of a flexible connection 48 is attached to the wire 43. Each station is further provided with a switch hook 49 depending from which is a latch 50. The switch hook 49 is adapted to 55 support a telephone receiver 51 substantially in the usual manner.

The relay 39 is provided with a swinging armature 52 which is retracted by means of a spring 53 and is supported upon a pivot 54. 60 This armature is provided with a lug 55 which normally prevents the switch hook 49 from rising except when the relay 39 is energized.

The lower end of the armature 52 opens 65 and closes a contact 56 with wires 57, 58, so as to connect these wires together when the relay is energized. The wire 58 is connected through a polarized bell 59 with a ground wire 60. The contact 45 is connected by a 70 wire 61 with a transmitter 62, the latter being connected by a wire 63 with the receiver 51. From this receiver a wire 64 leads to a wire 40.

Each switch hook 49 has a limited amount 75 of play even when locked as indicated, so that when the receiver 51 is removed from the hook the latter is free to rise to an extent which will permit the contact member 46 to come into engagement with the spring contact 44, thus completing a circuit through 80 the relay.

The operation of my system is as follows: Suppose that all of the stations are in their normal condition as indicated in the drawing. The switch hooks 49 are now locked 5 in their lowermost positions, that is, by the action of the lugs 55 are prevented from rising beyond certain limits. If now, a subscriber, say the one at station B, desires to converse with a subscriber upon some other 10 line, he takes off his receiver 51 and allows the hook 49 to rise; this brings the contact member 46 into engagement with the contact member 44 and completes the following circuit: battery 4 at central station, wires 15 6, 7, line relay 5, wire 12, jack 13, wire 38, to station B, wire 43, flexible connection 48, contact members 46, 44, wire 41, high resistance relay 39, wire 40, line wire 37, jack 13, wire 14, wire 3, back to battery 4. This 20 energizes both the line relay 5 at the central station, and the high resistance relay 39 at the station of the calling subscriber. The line relay 5 attracts its armature 8 and closes the contact 9, thereby completing the following 25 circuit: battery 4, wire 6, wire 10, contact 9, armature 8, wire 11, line lamp 1, wire 2, and wire 3, back to battery 4. The circuit last traced is in effect a short circuit from the battery 4 through the line lamp 1. 30 The completion of the circuit through the high resistance relay 39 energizes the latter and causes it to attract the armature 52 which in moving takes the lug 55 out of the path of the latch 54 and allows the hook to 35 rise into its uppermost position. The switch hook 49 having risen to its uppermost position, the contact members 46 and 45 are now in mutual engagement, hence there is a metallic circuit from line wire 38 to line wire 40 40 through the medium of wire 43, flexible connection 48, contact members 46, 45, wire 61, transmitter 62, wire 63, receiver 51, wire 64, and the lower portion of wire 40. The subscriber at station B, by using the transmitter 62 and receiver 51 can now talk to the 45 central operator, the latter having been apprised by the glow of the line lamp 1, that somebody upon the line desires to talk. The central operator then inserts the plug 15 50 into the jack 13, ascertains in the conventional manner the purport of the call, and then, if necessary, inserts the plug 31 into the jack of some other line so as to place the calling subscriber in communication with the 55 party desired. The talking circuit is as follows: transmitter 62 at station B, wire 61, contact members 45, 46, flexible connection 48, wire 43, line wire 38, lower contact of jack 13, plug 15, wire 17, contact members 60 19, 36 of ringing key 18, wire 35, winding 33, battery 34, winding 29, wire 27, contact members 28, 20, wire 16, plug 15, jack 13, wire 37, wires 40, 64, receiver 51, wire 63, back to transmitter 62. The windings 29, 65 33, being thus energized, act inductively

upon the windings 29^a, 33^a, and these act in the usual manner through wires 30, 32, plug 31 and battery 34, to the line called.

While the circuit is in the condition just described or in other words, while the subscriber at station B has his receiver 51 off the hook, no other subscriber upon the line can use his telephone or in any way interfere. For instance, if the subscriber at station A removes his receiver 51, the switch hook 49 will not rise because the switch hook is locked down and the high resistance relay 39 controlling it cannot be energized; to be sure, at station A the contact member 46 engages the contact member 44 but this has no effect upon the relay 39 owing to the fact that this high resistance relay is short circuited by the low resistance talking circuit at station B; or in other words, by the metallic circuit at station B, consisting of 85 wire 43, flexible connection 48, contact members 46, 45, wire 61, transmitter 62, wire 63, receiver 51, wire 64, and lower part of wire 40, and any and all subscribers upon the party line, except the one who first removed 90 his receiver, are therefore locked out. The conversation being completed, the subscriber at station B hangs up his receiver 51 and thus restores the line to normal condition as shown in the drawing. 95

Suppose, now, that the central operator desires to call the subscriber at station A. The central operator inserts the plug 15 into the jack 13 and depresses the ringing key 18. The following circuit is thus completed: 100 ground wire 26, generator 25, wire 23, contact members 24, 20, wire 16, plug 15, jack 13, line wire 37, wire 40, high resistance relay 39, wire 41, condenser 42, wire 43, wire 38, jack 13, plug 15, wire 17, contact members 19, 22, wire 21, back to ground. This energizes the high resistance relay 39 and causes it to attract its armature 54. This not only completes the metallic connections from line wire 38 to line wire 37, as above 110 described but also closes the contact 56 and in so doing allows the current from the line wire 37 to pass simultaneously through the polarized bell 59. The ringing, therefore, takes place over the following circuit: ground 115 wire 26, generator 25, wire 23, contact members 24, 20, wire 16, plug 15, jack 13, wire 37, wire 57, contact 56, polarized bell 59, wire 60, to ground, then back to ground wire 26 at central station. This rings the bell 120 59 and the subsequent steps are well known.

It will be noted that when a subscriber upon the party line is calling the operator at the central station, the high resistance relay 39 at the station of the calling subscriber 125 is energized by the battery 4 at the central station; but that when the central operator is calling a subscriber upon the party line, the current for energizing the relay 39 is supplied from the generator 25 and not from 130

the battery 4. It appears therefore, that in one instance, the high resistance relay 39 is energized from one source of electricity for one purpose, and in another instance is energized by another source of electricity for another purpose; also that this relay performs a dual office, to wit: It controls the position of the switch hook and thus controls the lockout of each station, and it also 10 temporarily throws into circuit the polarized bell 59; this bell therefore, never ringing except when and during the time the relay 39 is energized by the ringing current from the generator 25.

15 I do not limit myself to any particular form of line upon which my invention may be used. Neither do I limit myself to any particular arrangement of the circuits, nor to the mechanism shown for enabling the 20 high resistance relay to control the lock-out.

Having thus described my invention I claim as new, and desire to secure by Letters Patent:—

1. The combination in a party line telephone system, of a relay provided with a 25 movable armature, a lockout controllable by said armature, a contact for controlling said relay, a movable switch hook for automatically closing said contact, a source of electricity normally connected to the line and with said contact for energizing said relay, a circuit provided with a contact to be opened and closed by movements of said armature, and an electric alarm connected with said 35 circuit and a second source of electricity, capable of operating both relay and alarm when connected to the line.

2. The combination in a party line telephone system of a switch hook, mechanism 40 for preventing the movement thereof beyond a predetermined limit, a relay connected with said last-mentioned mechanism for the purpose of permitting the movement of said switch hook beyond said predetermined limit, said relay being energized automatically by a source of electricity normally connected to the line through movements of said switch hook, and a normally open circuit provided with a contact to be closed 50 by said mechanism.

3. The combination in a party line telephone system of a movable switch hook, a movable armature for locking said switch hook in a predetermined position, a magnetic 55 member controllable electrically through a contact at said switch hook for the purpose of attracting said armature and thereby releasing said switch hook, a contact to be closed by said armature, a bell circuit connected with said contact and controllable thereby, and means controllable from a 60 distance for energizing said magnetic member and said bell circuit at practically the same instant.

65 4. The combination in a party line tele-

phone system of a high resistance magnet, a direct current circuit for energizing said magnet, said circuit being normally open, a switch contact for closing said circuit, a lockout controllable by said magnet, an 70 alternating current circuit for energizing said magnet, a contact to be actuated by said magnet, a high resistance circuit including a bell and adapted to be controlled by closure of said contact, and means controllable at will from a distant station and common to said magnet and to said bell for energizing the same independently of said first-mentioned source of electricity.

5. The combination of line conductors, a 80 high resistance magnet disposed at a subscriber's station, a lockout controllable by said high resistance magnet, a direct current source of electricity located at a central station and normally connected to said line conductors for signaling and talking purposes, said direct current source of electricity being controllable at will from a subscriber's station for energizing said magnet, an alternating current source of electricity located at 90 said central station and controllable therefrom for the purpose of energizing said magnet independently of the will of the subscriber, and alarm and talking circuits located at said subscriber's station and both 95 controllable by said high resistance magnet.

6. The combination of a line, a plurality of high resistance relays connected therewith and each located at a subscriber's station, a source of electricity located at a central station and connected to said line, said source of electricity being controllable at will from any subscriber's station for energizing said relay at that station, an alternating current source of electricity controllable at will from 105 a central station for simultaneously energizing all of said relays independently of the wills of the subscribers, a low resistance talking circuit at each subscriber's station, means located at each subscriber's station and controllable by the individual subscriber for shunting said talking circuit across the relay, and an electric alarm located at each subscriber's station and controllable by the relay at that station for the purpose of giving a 110 signal continuously so long as said line is energized from said alternating current source of electricity.

7. In a party line telephone system, the combination at a subscriber's station of a 120 movable switch hook, a high resistance magnet provided with means for controlling movements of said switch hook beyond a predetermined limit, a contact in said magnetic circuit adapted to be closed by said 125 switch hook before arriving at said predetermined limit, a low resistance talking circuit normally open and adapted to be closed by movements of said switch hook beyond said predetermined limit, and a normally open 130

bell circuit provided with a contact to be closed by action of said high resistance magnet.

8. In a party line telephone system, the combination at a subscriber's station of a movable switch hook, a locking device therefor, a high resistance relay provided with means controllable by said switch hook for actuating said locking device so as to release said switch hook, an electric alarm controllable by said relay, a talking circuit bridged around said relay and provided with a contact to be closed by the movement of said switch hook when the latter is released, and means for energizing said high resistance relay, independent of said first mentioned means, and independently of the will of a subscriber at said subscriber's station.

9. In a party line telephone system, the combination at a subscriber's station of a high resistance relay, a source of electricity controllable by a switch hook contact at said station for energizing said relay, lockout mechanism controllable by said relay, a contact to be opened and closed by said relay, an electric alarm controllable by said contact, and means under control of a central station for energizing said relay independently of said first-mentioned source of electricity, and a normally open low resistance talking circuit controllable by movements of said switch hook, and located in a branch circuit about said relay.

10. The combination of a transmitter circuit at a subscriber's station, lockout mechanism for holding the same temporarily incomplete, a high resistance relay connected to the line and in a circuit controllable by a switch hook at said station for operating said lockout mechanism, said relay being provided with a contact, an electric alarm connected with said contact, and a source of alternating current located at a central station, means for connecting said source of alternating currents with said high resistance relay for the purpose of energizing the same and also energizing said alarm mechanism.

11. In a party line telephone system, the combination at a subscriber's station of a transmitter circuit, lockout mechanism for holding the same temporarily incapable of being connected to the line, a high resistance relay for controlling said lockout mechanism, means at said subscriber's station for connecting said relay to the line, said relay being provided with a contact, an electric alarm connected with said contact, a source of alternating current located at a central station for the purpose of energizing said relay and said alarm mechanism, and a condenser interposed in a branch circuit of said alternating current and said relay about said open point at said switch hook contact.

12. The combination of a line extending

from a central station to a subscriber's station, a transmitter at a subscriber's station connected to the line, lockout mechanism for holding said transmitter temporarily in an open circuit, a high resistance relay for controlling said lockout mechanism, means at said subscriber's station for connecting said relay to the line, said relay being provided with a contact, an electric alarm connected with said contact, a source of alternating current located at a central station for the purpose of energizing said relay and said alarm mechanism, and a condenser interposed in the circuit of said alternating current and said relay.

13. The combination of a line extending from a central station and a sub-station, a relay located at said sub-station, a condenser connected with said line and with said relay so that said relay may be actuated through said condenser, a bell circuit controllable by said relay, a generator located at said central station for the purpose of operating said relay and energizing said bell circuit, a source of electricity normally connected to the line and located at said central station and independent of said generator, and mechanism at said sub-station for short-circuiting said condenser and allowing said relay to be actuated from said second-mentioned source of electricity.

14. The combination of a line extending from a central station and a sub-station, a relay located at said sub-station, a condenser connected with said line and with said relay so that said relay may be actuated through said condenser, a bell circuit controllable by said relay, a generator located at said central station for the purpose of operating said relay and energizing said bell circuit, a source of electricity normally connected to the line and located at said central station and independent of said generator, mechanism at said sub-station for short-circuiting said condenser and allowing said relay to be actuated from said second-mentioned source of electricity, and lockout mechanism controllable by said relay.

15. In a party line telephone system, the combination at a subscriber's station of a circuit normally open to the passage of a direct current and closed to the passage of an alternating current, a relay included in said circuit and adapted to be energized thereby, and means for connecting said relay in a second metallic circuit to the line.

16. In a party line telephone system, the combination at a subscriber's station of a circuit normally open to the passage of a direct current and closed to the passage of an alternating current, and a relay included in said circuit and adapted to be energized thereby, means including a movable switch hook for connecting said relay in a separate

metallic circuit to the line, and an electric alarm circuit to be opened and closed by said relay.

17. In a party line telephone system, the combination at a subscriber's station of a circuit normally open to the passage of a direct current and closed to the passage of an alternating current, and a relay included in said circuit and adapted to be energized thereby, means including a movable switch hook for connecting said relay in a separate metallic circuit to the line, an electric alarm circuit to be opened and closed by said relay, and a lockout controllable by said relay.

18. In a party line telephone system, the combination at a subscriber's station of a circuit normally open to the passage of electricity, a relay included in said circuit, a second circuit allowing the passage of alternating current but not allowing the passage of direct current through said relay, and means controllable by a contact at said subscriber's station for allowing the passage of direct current through said relay.

19. In a party line telephone system, the combination at a subscriber's station of a circuit normally open to the passage of electricity, a relay included in said circuit, a sec-

ond circuit allowing the passage of alternating current but not allowing the passage of direct current through said relay, signaling and lock-out devices, and means for allowing the passage of either of said currents, for controlling said signaling and lockout devices.

20. In a party line telephone system, the combination at a subscriber's station of a circuit normally open to the passage of electricity, a relay included in said circuit, a second circuit allowing the passage of alternating current but not allowing the passage of direct current through said relay, signaling and lock-out devices located at said subscriber's station, means at said subscriber's station for allowing the passage of direct current through said relay for controlling said lockout devices, and means at a central station to operate said relay to control said signaling devices at said subscriber's station.

In testimony whereof I have signed my name to this specification in the presence of two subscribing witnesses.
